Attorneys.

UNITED STATES PATENT OFFICE.

RAYMOND C. BENNER, OF BAYSIDE, NEW YORK, ASSIGNOR TO THE PREST-O-LITE COMPANY, INC., OF NEW YORK, N. Y., A CORPORATION OF NEW YORK.

ELECTRIC STORAGE CELL.

Application filed January 13, 1923. Serial No. 612,513.

This invention relates to storage cells of the type adapted for the operation of hand lamps, or the like. The invention resides in certain features of construction, including 5 an electrode assembly readily removable as a unit from its casing, means for minimizing the likelihood of charging the cell while improperly positioned, an auxiliary contact-carrying cap adapted for removable attachment to the cell, and other novel and advantageous arrangements.

The improved constructions will be described in detail in connection with the accompanying drawings, in which—

15 Fig. 1 is a vertical central section through one embodiment of the invention, showing the end caps adjacent the body of the cell;

20 Fig. 2 is a sectional illustration of the removable electrode assembly;

25 Fig. 3 is a partial sectional view of a cell of the type shown in Fig. 1, but having a modified form of bottom cap; and

Fig. 4 is a partial sectional view of the improved cell provided with an auxiliary contact carrying head.

Referring to Figs. 1 and 2, reference numeral 1 denotes a case of suitable insulating material, such for example as hard rubber or a phenolic condensation product, adapted 10 to withstand the action of the electrolyte. Ferrules 2 and 3 are secured at the ends of the casing. A closure 4 is adapted for engagement with ferrule 2 and carries tubular metallic inserts 5 and 6 adapted to receive 15 lugs on electrodes 7 and 8, respectively.

The electrodes may be formed of any suitable positive and negative active material, which may be supported by a plate or grid (not shown) in a manner well understood in the art. An electrolyte absorbent 9 is placed about the electrodes. A composition comprising an absorptive organic material and a fibrous mineral material, such as that described and claimed in my copending 10 patent application Serial No. 552,834, filed April 11, 1922, is preferably used as the absorbent. A perforated disc 9' is placed at the inner end of the electrodes to retain the absorbent while permitting escape of gas.

20 The closure 4 may conveniently be constructed by molding a plastic insulating material into a block 10 surrounding the

tubular inserts 5 and 6 and receiving a flange 11 on a threaded ring 12. The flange 11 is preferably loosely held in the recess 55 11' in block 10, so that the block will not rotate with ring 12 but will be moved directly inward when the ring is tightened. The block forced in this manner against gasket 12' makes a tight joint with the 60 casing 1.

When the cell is to be used in flashlight operation, a metal plate 13 is set in the surface of block 10 and in circuit with one of the electrodes (8). Upon inserting the cell 65 in the usual flashlight casing, the inner terminal of the lamp bulb will make contact with plate 13, and through this with tube 6 and electrode 8. A conductor strip 14 is in contact with the other electrode, 7, and extends longitudinally of the cell to engage ferrule 3, which affords a metallic contact at the end of the cell remote from the lamp. A metallic cap 15 is threaded to engage 70 ferrule 3, and contains a gasket 15' to insure 75 an effective seal with the casing when the cap is placed in position.

It will be noted that there are exposed metallic contacts of opposite polarity at each end of the cell, and that it may therefore be used in flashlight operation in the same manner as a dry cell or battery of dry cells. This is an important advantage of the present cell, as it obviates the necessity 80 for the flashlight casings of special construction which are usually required to accommodate storage cells.

A ring 16, preferably of celluloid, is fitted in the casing 1 and carries a hollow conical member 17, in which a fibrous material 18 90 is contained. Absorbent pads 19 are placed above the fibrous material. The construction just described forms a combined acid trap, vapor arrester, and absorption device. The chamber 20 about the smaller end of cone 17 operates as an acid trap and has sufficient capacity to receive any acid which may escape by gravity flow from the absorbent. The fibrous material 18 is preferably oiled glass wool, which effectually prevents the passage of moisture entrained by gases passing from the cell to vent 21 in cap 15. The pads 19 may be saturated with proper reagents to render the gases harm-

less. The combination of acid trap, vapor arrester and absorbent means described is not claimed herein, as this construction forms part of the subject matter claimed in my copending application Serial No. 585,960, filed September 2, 1922.

10 A cap 22, containing an insulating block having recesses 23 and 24 to receive the projecting ends of tubes 5 and 6, is adapted to be fitted upon ferrule 2. The cap is provided with a perforation 25 to permit the passage of the stem of a lamp bulb.

15 When it is desired to replace the current-producing elements, the closure 4 is unscrewed and removed from the casing, bringing with it the electrodes and absorbent. An electrode assembly adapted for refilling the casing is illustrated in Fig. 2. The new assembly is inserted in the casing and the 20 closure screwed in until a tight joint is made by compression of gasket 12'. The cap 15, pads 19, and glass wool 18, are then removed, and the proper amount of acid is poured in through cone 17. The cell may be charged 25 in the usual manner, either before or after replacing the glass wool, pads, and cap. The tubes 5 and 6 receive the terminals of the charging circuit.

20 The electrode assembly may be wrapped 30 in a suitable material 33, such as paper, to prevent loss of the electrolyte absorbent 9. The assembly may be made of such size as to slip easily into the casing. On addition of electrolyte, absorbents of the type 35 described swell to a considerable extent, insuring the complete filling of the casing and making good contact with the electrodes.

30 Properly constructed storage cell casings are relatively expensive and appreciable loss 40 is involved by discarding the casing when the current-producing elements become unserviceable. Heretofore electrodes have been 45 banded together to form a removable unitary structure for immersion in a jar or the like containing electrolyte, but such devices are inapplicable to cells of the type referred to herein. So far as I am aware, no flashlight 50 storage cell having a readily renewable electrode assembly had been proposed prior to my invention. As described herein, a unitary construction is provided whereby the 55 user of the cell may replace both the electrodes and the absorbent in a simple and convenient manner.

55 In order to prevent charging of the cell while the electrolyte chamber is elevated with respect to the absorbent pads, I provide an end cap construction such as shown in Fig. 3. The device there illustrated is 60 the same as that of Fig. 1, except that a rounded cap 26 is provided. It is accordingly impossible to stand the cell on the end containing the absorbent, and charging while the cell occupies that position is ordinary 65 prevented. The downflow of acid

from the electrolyte absorbent during charge may be sufficient to destroy the effectiveness of the gas absorbent, and it is therefore important to insure that the cell shall be correctly positioned at this time. The rounded 70 contour of the cap will not interfere with the use of the cell in flashlight operation.

75 In Fig. 4 is shown an auxiliary cap for use with cells of the type described, or with other suitable cells. This cap consists of 80 a ring 27, having a press-fit with the smooth upper portion of ferrule 2, and an insulating top 28 in which binding posts 29 and 30 are set. Resilient metallic members 31 and 32 are secured to the bottoms of the 85 binding posts 29 and 30, respectively, and engage tubes 5 and 6. When the flashlight cell is desired for other uses, the auxiliary cap may be affixed and the binding posts utilized in the usual way.

90 The advantages of the invention are not dependent upon the specific constructions illustrated, and various changes in such constructions may be made within the scope 95 of the appended claims.

I claim:—

1. A storage cell comprising a casing, means at one end of the casing for absorbing 95 harmful gases, an electrode and electrolyte absorbent assembly positioned in the opposite end of the casing and fitting snugly within the same, and means whereby said assembly may be removed as a unit from said casing.

2. A flashlight storage cell comprising a casing, means at one end of the casing for absorbing harmful gases, a closure for the opposite end of the casing, an electrode and electrolyte absorbent assembly fitting snugly within the casing, said assembly being carried by said closure and removable as a unit therewith.

3. A storage cell comprising a casing, means for absorbing harmful gases, an electrode and electrolyte absorbent assembly positioned within and snugly fitting the casing, and means whereby said assembly may be removed as a unit from said casing and the rest of the cell.

4. A flashlight storage cell comprising a 11 casing, means for absorbing harmful gases, a closure for one end of the casing, an electrode and electrolyte absorbent assembly fitting snugly within the assembly and carried by said closure, said closure and assembly being removable as a unit from said casing and the rest of the cell structure.

5. A flashlight storage cell comprising a 12 casing, an electrode and electrolyte absorbent assembly positioned within and snugly fitting the casing and removable as a unit therefrom, means for absorbing harmful gases adjacent one end of the casing, a removable closure for one end of the casing 13 adapted to be engaged by the inner terminal

- of a lamp bulb, a removable closure for the other end of the casing carrying a second contact member, and means for placing the contact members in electrical connection with cell electrodes of opposite polarity.
6. A storage cell for actuation of flashlights and other purposes, comprising a casing, electrodes and electrolyte in operative relation therein, conductive means in electrical connection with the electrodes and adapted for use in cooperation with the electrical circuit of a flashlight, and an auxiliary cap adapted to fit onto the end of the casing and carrying binding posts connectible with the electrodes, whereby the cell is fitted for general use when the auxiliary cap is placed thereon.
7. An assembly for renewal of the current-producing elements of a storage cell, comprising a closure for one end of the cell, contact members in the closure, electrodes carried by the closure and electrically connected to the contact members, an electrolyte absorbent about the electrodes, and means for retaining the absorbent, said assembly being adapted to be inserted in and withdrawn from the cell as a unit.
- In testimony whereof, I affix my signature.

RAYMOND C. BENNER.
